UNITED STATES PATENT OFFICE.

EUGENE P. STARCKE, OF PORT ARTHUR, TEXAS.

CAN-CLOSURE.

1,327,067.

Specification of Letters Patent.

Patented Jan. 6, 1920.

Application filed December 10, 1918. Serial No. 266,080.

To all whom it may concern:

Be it known that I, EUGENE P. STARCKE, a citizen of the United States, residing at Port Arthur, in the county of Jefferson and State of Texas, have invented certain new and useful Improvements in Can - Closures, of which the following is a specification.

The invention relates to means for closing cans and like packages containing liquid, the purpose being to secure the can in a manner to prevent tampering with the contents without rendering detection possible and also to enable the contents of the can to be poured off without waste and likewise to guard against loss by evaporation and to prevent foreign matter finding its way into the can or package.

The invention provides a can closure which is adapted for general use and which maintains the discharge opening in closed position at all times, whether the sealing cap has been replaced or not, thereby preventing loss by evaporation and keeping the contents of the can from being impaired by the entrance of foreign matter into the can.

The drawing illustrates a preferred embodiment of the invention, however, it is to be understood that in adapting the same to meet different conditions, various changes in the form, proportion, and minor details of construction may be resorted to without departing from the nature of the invention as claimed hereinafter.

Referring to the accompanying drawing, Figure 1 is a top plan view of a can provided with closing means embodying the invention, the cap being omitted.

Fig. 2 is a sectional view on the line 2—2 of Fig. 1, the cap being in position.

Fig. 3 is a section on the line 3—3 of Fig. 2, the cap being omitted and the inner cylinder or spout drawn upward.

Fig. 4 is a detail view in elevation, the cap and outer shell being detached from the collar.

Corresponding and like parts are referred to in the following description and indicated in the several views of the drawing by like reference characters.

The numeral 1 designates a can, package or container of any type adapted to be supplied with closing means embodying the invention. The top of the can or container 1 is provided with an opening which is located in one corner and from which projects a collar 2. An inner shoulder 3 is provided at

the upper end of the collar 2 and forms a support for a packing ring or gasket 4. A cylinder 5 is disposed within the collar 2 and is spaced therefrom and is connected at its upper end to the collar in any manner. The lower end of the cylinder 5 is closed, as indicated at 6, and receives a packing 7. Vertical slots 8 are formed in the sides of the cylinder 5 and constitute outlets, guide and stop means. The cylinder 5 depends from the inner edge of the shoulder or like part 3 and projects into the upper portion of the can a short distance.

A cylinder 9 telescopes within the cylinder 5 and is provided with outwardly extending lugs 10 which enter and operate in the vertical slots 8, whereby to limit the outward movement of the cylinder 9 and prevent its turning in the cylinder 5. The cylinder 9 is open throughout its length and constitute a spout through which the contents of the can are drawn off. An inner shoulder or flange 11 is provided at the inner or lower end of the cylinder 9 and is adapted to engage the packing 7 and obtain a close joint therewith to prevent any loss by evaporation. A valve 12 closes the outer end of the cylinder 9 and is of the butterfly type, being pivoted on a diametrical line. A tight joint is maintained between the cylinder 9 and the collar 2 by means of the packing 4 which has its inner edge engaging the outer side of the cylinder 9, said packing being retained in position by means of a shell 13 which is snugly fitted upon the collar 2 and is retained in place thereon by interengaging portions pressed outwardly from the collar 2 and shell 13. The shell 13 is provided at its upper end with an inner shoulder or flange 14 which overhangs the packing 4 and confines it between the parts 3 and 14. The upper portion of the shell 13 is formed with a screw-thread 15 which is adapted to engage a correspondingly threaded portion 16 of a cap 17 by means of which the closure is made secure. The cap 17 receives a packing 18 in a manner well understood which insures the formation of a tight joint when the cap 17 is properly positioned upon the shell 13.

The can, package or container 1 is provided with the collar 2 in any well known way and after being filled is adapted to have the closure secured in position by placing the shell 13 so as to embrace the collar, portions of the shell and collar being crimped

- by a suitable tool to prevent their separation. A sealing strip 19 extends over the valve 12 and is secured at its end to the shell preferably by being soldered thereto.
- 5 This prevents outward movement of the cylinder 9 and a turning of the valve 12 thereby preventing the contents of the can from being tampered with, thereby insuring to the customer the goods originally placed in the
- 10 can and as designated by the label applied to the can. When it is required to obtain the contents of the can the cap 17 is removed and the sealing strip 19 cut or otherwise displaced to admit of opening of the
- 15 valve 12 and the drawing outwardly of the cylinder 9 preliminary to pouring off the contents of the can therethrough. When not drawing off the contents from the can, the valve 12 remains closed and the cylinder 9 is
- 20 pressed inward, thereby doubly sealing the outlet even though the cap 17 is not replaced, since the inner end of the cylinder 9 is closed by the packing 7 and its outer end is closed by the valve 12. The provision of the cap 17
- 25 gives greater security and prevents any possible interference with the parts or the loss of the contents of the can, since it is positively held to the shell 13 and seal the same by means of the packing 18.
- 30 The foregoing description and the drawings have reference to what may be considered the preferred, or approved, form of my invention. It is to be understood that

I may make such changes in construction and arrangement and combination of parts, 35 materials, dimensions, et cetera, as may prove expedient and fall within the scope of the appended claim.

Having thus fully described my invention, what I claim as new and desire to secure by Letters Patent is:—

A can or container having an opening, a collar in line with the opening and having an inner shoulder at its outer end, a fixed cylinder depending from the inner edge of 45 said shoulder and having its inner end closed and longitudinal slots in its sides, a packing supported on the closed end of the fixed cylinder, a sliding cylinder within the fixed cylinder and having outwardly extending lugs entering the longitudinal slots there- 50 of, a valve at the outer end of the sliding cylinder, a packing supported on the inner shoulder of the collar and in close contact with the outer side of the sliding cylinder, a 55 shell secured to the collar and retaining the packing in position, a sealing member extending over the valve and secured to the shell and a cap threaded on the outer end of the shell.

In testimony whereof I affix my signature in presence of two witnesses.

EUGENE P. STARCKE.
